T. W. Burger,
 Steam-Boiler Water-Feeder,
 № 37,673. Patented Feb. 17, 1863

Inventor
 Theodore W. Burger

UNITED STATES PATENT OFFICE.

THEODORE W. BURGER, OF JERSEY CITY, NEW JERSEY.

IMPROVEMENT IN BOILER-FEEDERS.

Specification forming part of Letters Patent No. 37,673, dated February 17, 1863.

To all whom it may concern:

Be it known that I, THEODORE W. BURGER, of Jersey City, in the county of Hudson and State of New Jersey, have invented a new and useful Improvement in Self-Regulating Boiler-Feeders; and I do hereby declare that the following is a full, clear, and exact description of the same, reference being had to the accompanying drawings, forming part of this specification, in which—

Figure 1 is a horizontal section of a boiler-feeder constructed according to my invention, the plane of section being indicated by the line $y y$ in Fig. 2, which is a vertical section of the same in the plane indicated by the line $x x$ in Fig. 1.

Similar letters of reference indicate corresponding parts in both figures.

This invention relates to that class of boiler-feeders through which the water is fed into the boiler by gravitation through an opening, the height of which regulates the level to which it is supplied; and it consists in a certain arrangement of the chambers, valves, and ports, whereby the construction of such feeders is much simplified.

To enable others skilled in the art to make and apply my invention, I will proceed to describe its construction and operation.

A is a box, divided by a vertical plane partition extending all across, and a second vertical partition, b' , extending from the said partition b to the outer side, into three chambers, c , d , and e , of which c may be termed the "inlet-chamber," d the "measuring-chamber," and e the "feeding-chamber."

The supply-pipe leading from a reservoir at any elevation above the box A is connected with the inlet-chamber at f , and the lower part of the feeding-chamber e is connected at g with the boiler, the top of the opening g or of the opening of the pipe connecting it with the boiler being at the level at which it is desired the boiler shall be filled. In the lower part of the partition b there are two ports, h and i , one on each side of the partition b' , one communicating with the inlet-chamber c and the other with the measuring-chamber d .

B is a slide-valve, arranged within the feeding-chamber and working horizontally between suitable guides, $j j$, on a seat formed upon the inner side of the partition b , and having a cavity, K, in its face long enough to cover or nearly cover the two ports $h i$ at the same time. This valve has attached to it a stem, l , which works through a stuffing-box at one end of

the feeding-chamber e , and which is connected with the steam-engine to which the boiler supplies steam, or with any other suitable motor for the purpose of giving to the valve a regular reciprocating rectilinear motion over the ports $h i$.

The operation is as follows: The movement of the valve in the direction of the red arrow (shown in Fig. 1) brings the chambers c and d into communication through ports $h i$, and valve-cavity k , as shown in that figure, and its movement in the opposite direction closes the port i , thereby shutting off the chamber c from the chamber d and uncovers the port h , thereby bringing the chamber d into communication with the chamber e . The chamber c is always full of water. By the first mentioned movement of the valve the water is permitted to flow from the chamber c into the chamber d and fill the latter chamber, and by the movement in the opposite direction the water is permitted to flow from the chamber d into the chamber e , whence it flows into the boiler by gravitation whenever the level in the latter is below the top of the opening g , so that steam can pass from the boiler through the said opening to place the water in the chamber e in *equilibrio* with that in the boiler. When the water in the boiler is high enough to cover the top of the opening g , the pressure of the steam therein prevents the entrance of any more from the chamber e ; but as soon as the said water gets low enough to uncover the top of the said opening more enters from the chamber e with every movement of the valve B in the direction of the red arrow. The operation is assisted by the formation of a vacuum in the measuring-chamber d and inlet-chamber c by the condensation therein of steam, which has been admitted to the chamber d while the port h was uncovered, and which is afterward allowed to enter the chamber c and shut off from the boiler by the closing of the port h to the chamber e , and the vacuum thus produced may render it unnecessary to place the reservoir above the box A.

What I claim as my invention, and desire to secure by Letters Patent, is—

The arrangement of the chambers $d c e$, valve B, and ports $h i$, substantially as and for the purpose herein specified.

THEODORE W. BURGER.
